(57) **CLAIM**

The ornamental design for a medical device to relieve symptoms of migraines, as shown and described.

DESCRIPTION

FIG. 1 is a top front isometric view of a medical device to relieve symptoms of migraines showing the new design;

FIG. 2 is a front elevational view thereof;

FIG. 3 is a rear elevational view thereof;

FIG. 4 is a left elevational view thereof, the right elevational view is a mirror image of the left elevational view;

FIG. 5 is a top plan view thereof; and,

FIG. 6 is a bottom plan view thereof.

In the drawings, the broken lines depict portions of the medical device to relieve symptoms of migraines that form no part of the claim.

1 Claim, 6 Drawing Sheets
